UNITED STATES PATENT OFFICE.

FRANZ GEISSLER, DECEASED, LATE OF COTTBUS, GERMANY, BY MARIANNE GEISSLER,
TRUSTEE, OF COTTBUS, GERMANY.

APPARATUS FOR DYEING WOOL AND OTHER FIBROUS SUBSTANCES.

1,267,209.

Specification of Letters Patent. Patented May 21, 1918.

Application filed August 14, 1916. Serial No. 114,929.

To all whom it may concern:

Be it known that I, MARIANNE GEISSLER, the widow of the deceased FRANZ GEISSLER, manufacturer, a subject of the King of Prussia, and resident of Cottbus, in the Kingdom of Prussia, by will of her deceased husband, the said FRANZ GEISSLER, am acting for his heirs; and that my husband, the said FRANZ GEISSLER, before his death, 5 had invented new and useful Apparatus for Dyeing Wool and other Fibrous Substances, 10 of which the following is a specification.

The present invention relates to a novel apparatus for dyeing wool and other loose 15 fibrous substances, rags and artificial wool, and has the object to be directly employed in machines which are adapted for dyeing 20 yarn in skeins or in cops. The use of the apparatus according to the present invention will, therefore, convert such dyeing machines into wool dyeing machines.

The present invention consists essentially 25 of a four cornered box of the same outer size as the inset boxes used in skein or cop 30 dyeing machines and the like. The essential feature of the box is that it may be opened both at the top and at one side, and that the opening at the top is rendered possible by the lid being removable, while for 35 opening the box at the one side the whole one side is removed. When such side has been fitted, and only the lid has been removed, the box must possess such reinforcement, that the wool may be stamped into it.

35 In the accompanying drawing an apparatus according to the present invention is exemplified.

Figure 1 is a diagram of a cop dyeing machine, in which an apparatus of the present kind has been substituted for the usual 40 box.

Fig. 2 is a plan view, partly shown in horizontal section, through the machine according to Fig. 1.

45 In the dye vat *a* the dye liquor is moved by means of a mechanical contrivance *b*, preferably in such a manner that it will flow through the material to be dyed alternately in one and the opposite direction.

The apparatus according to the present 50 invention consists of a box with a perforated bottom *c* and also a perforated lid *d*. Into the bottom a number of posts *e*, in the embodiment shown six, are secured, preferably by means of dovetails. These posts have 55 vertical grooves *e*¹. Into these grooves the boards *f* forming the sides are fitted. Above the level of the liquid the posts are joined together by means of suitable cross beams *g*. On the longitudinal side they are fur- 60 thermore joined together by laths *h*, which form a guide for the lid *d*. The said lid *d* is slid into the groove formed by said laths. In a similar manner the one side wall *i* is slid into vertical grooves, which are 65 cut in the posts directly, or which are formed by nailing separate vertical laths *i*¹ to the same. The lid *d* projects on the right side beyond these guide grooves so that when the side wall *i* is slid into its vertical 70 grooves, and the lid *d* is fitted into its grooves, the said lid will cover the upper edge of the side wall *i*, so that the latter cannot be removed, without the lid having 75 been previously removed.

The apparatus is employed in the following manner:

The box is assembled so that it forms a complete box with the exception of the lid *d*, the side wall *i* thus being fitted into position. Then the box is filled with wool, whereupon the perforated lid is fitted into position and the box is lowered by aid of a hook screwed into the cross beam *g* into the dyeing machine. When the dyeing 80 process is completed, the box is lifted in a similar manner from the dyeing machine. The lid is then opened, the side *i* removed and the whole box may be easily emptied 85 at one time.

90 I claim:

1. Apparatus for dyeing wool consisting of a box, adapted to the shape of yarn dyeing machines, both the lid and one side of said box being removable.

2. Apparatus for dyeing wool consisting of a box, adapted to the shape of yarn dyeing machines, both the lid and one side of

2
said box being removably guided in grooves in said box, the lid, when in position, overlapping the upper edge of the said removable side.

- 5 In testimony that I claim the foregoing as the invention of my deceased husband, the above-mentioned FRANZ GEISSLER, I have

signed my name, in presence of two witnesses, this 25th day of July, 1916.

MARIANNE GEISSLER,
Widow of the deceased Franz Geissler.

Witnesses:

HENRY HASPER,
ALLEN F. JENNINGS.
